(57) **CLAIM**

The ornamental design for a watering wand, as shown and described.

DESCRIPTION

FIG. 1 is a front, left and top perspective view of a watering wand, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged view of portion 8 encircled in FIG. 1; and,

FIG. 9 is an enlarged detail view of portion 9 encircled in FIG. 1.

Broken lines illustrate portions of the watering wand that form no part of the claimed design.

1 Claim, 9 Drawing Sheets
